HIGH-TEMPERATURE CONDUIT

Louis Joe Weber, Borger, Tex., assignor to Phillips
Petroleum Company, a corporation of Delaware

Application November 13, 1944, Serial No. 563,213

11 Claims. (Cl. 138—64)

1

This invention relates to high temperature conduits. In one of its more specific aspects it relates to the insulation of any pipe or vessel by means of heat insulation inside the stress-bearing portion thereof. In one of its more specific aspects it relates to pipe for transporting very hot liquids, gases, or vapors.

More specifically, my invention consists of three-element structure comprised of: (1) a thin-walled and unpressed inner conduit formed of a material resistant to corrosion or oxidation by extremely hot gases; (2) a concentric outer shell of ordinary structural material such as low-carbon steel, for example, which will satisfactorily bear the pressure stresses as long as the temperature of the shell is not excessive; and (3) a layer of suitable insulating material interposed between the two concentric shells to insure maintenance of the outer shell temperature below the allowable limit.

In the past, many alloy steels have been developed for use in high temperature applications, such as in steam superheaters, petroleum cracking stills etc. These alloys were developed to answer two specific problems. One problem is in the overcoming of rapid corrosion effect of high temperature steam and/or organic gases upon equipment constructed of the early common types of steel. The second advantage gained by the introduction of these special alloy steels was an improvement in tensile strength at elevated temperatures.

While the advantage of the special alloy steels is great in regard to corrosion resistance, the improvement in strength characteristic as compared to ordinary steels is not proportionate to the increased cost of the alloy materials. The result is that equipment for high temperature application (where high pressures are usually corollary) is designed to employ either the alloy materials at a great money expense, or the ordinary steels at a lesser expense but a still considerable one and with the disadvantage of great bulk in the structure.

In my improved construction, the expensive corrosion-resistant alloy materials may be used sparingly with maximum benefit. The stress-bearing portion of the structure is protected from both high temperature and corrosive action, so that the less costly common steels can be used without undue sacrifice with respect to strength, bulk or cost of the equipment to be fabricated. A further advantage is realized in that less heat is lost from the system per unit of time, with the dual effect of conserving the heat energy and

2

minimizing the discomfort to be inflicted upon the operating personnel, as well.

For example, one particular application for which my improvement has great utility is in a process for treating hydrocarbons, wherein it is necessary to cool the effluent from a reaction vessel from 1500° F. down to about 850° F., at a sustained pressure of approximately 100 pounds per square inch. The required cooling is carried out in a heat exchanger in which the hot gaseous material is passed around a number of pipes containing water (steam) as a coolant. The gases to be cooled contain various hydrocarbon vapors, and often an appreciable quantity of sulphur, in which latter case the corrosive action is especially severe.

On the basis of results obtained in an experimental cooler incorporating my improved construction, the indicated cost of the cooling unit and adjacent piping for a commercial application would be but a fraction of that which would be incurred in conventional fashion, or if available commercial heat exchangers were to be modified for the purpose.

25 A principal object of my invention is to provide a relatively inexpensive structure for the handling of extremely hot gases and vapors.

30 A more specific object is to make practical the use of ordinary carbon steels for the stress-bearing members in an application where the conditions of temperature and corrosion have heretofore required the use of more expensive special alloy steels.

35 A further object is to reduce the effect of differential expansion in the stressed portions of piping systems by holding the maximum temperature of those parts well below the values obtaining in the case of conventional structure in the same high-temperature service.

40 It is an object to reduce the amount of heat lost to the atmosphere in a system of the sort herein described, with a consequent increase in the amount of useful by-product heat recovered in the cooling system.

45 Another object is to provide, in a unit of the nature to be described, full protection against corrosive attack with a minimum expenditure of special corrosion-resistant alloy.

50 It is an object to provide a section of such a conduit having easily assembled and disassembled parts which sections of the conduit are readily removed and replaced without substantial longitudinal movement and without telescoping, in which flow deflectors and baffle plates prevent or minimize by passing of fluid behind the heat

insulation with resultant hot spots in the stress bearing shell, and in which suitable construction is provided to prevent collapse of the intermediate and inner portions upon pressure fluctuations.

Numerous other objects and advantages will be apparent to those skilled in the art upon reading the accompanying specification, claims and drawings.

In the drawing:

The single figure of the drawing is a cross sectional view taken along the longitudinal axis of a high temperature conduit embodying my invention.

Said high temperature conduit, generally designated as 2, is formed generally as a three element structure comprising a thin walled, unpressured inner conduit 3 formed of a material resistant to high temperatures and preferably resistant to corrosion or oxidation by extremely hot fluids, a concentric outer shell 4 of ordinary structural material, such as low carbon steel, for example, which will satisfactorily bear the pressure stresses as long as the temperature of the shell is not excessive, and the layer of suitable heat insulating material 5 interposed between the inner conduit 3 and the outer shell 4 to insure maintenance of the outer shell temperature below the allowable limit.

Outer shell 4 may be any pipe suitable for ordinary low temperature conduits. The sections of pipe 4 may be secured together by any well-known means in the practice of the present invention, but as an illustrative embodiment of a preferred form of attaching means, pipes 4 are shown connected by means of flanges 6, studs 7 and nuts 8. While flanges 6 could be secured to pipe 4 by screw threads or other means in the practice of the present invention they are shown secured by welds 9 and 11. The exact form of welds 9 and 11 is not important.

While flanges 6 may in many instances be drawn directly together, it is considered good practice to provide a suitable gasket 12 between them. Gasket 12 may be made of felted asbestos which may or may not be impregnated with a suitable sealing compound depending on the nature of the fluid being transported in the conduit 2, and many such gaskets are for sale for use with various fluids, some of these gaskets having a thin sheet metal cover (not shown) over the asbestos.

The outer stress bearing shell 4 is of course imperforate. Supported inside shell 4 is an intermediate heat insulating shell 5. The shell 5 may be cast in place between shells 3 and 4 in which case the natural bond between the material of shell 5 and shells 3 and 4 serves to reduce the danger of fluids bypassing or channelling between shells 3 and 5 or 5 and 4.

However it is contemplated as a modification (not shown) to form shells 3 and 5 in a separate mold of the usual type so that they may be provided as integral preformed interior sections to be inserted when desired in ordinary exterior pipe like 4.

In either modification it is desirable to provide an annular imperforate baffle plate 13 sealed to the exterior shell 4 by suitable means, such as weld 14. In the case of the cast in place lining 5, baffle 13 will aid in supporting the material during casting, and in the case of the inserted type of liner 5 the liner can be inserted from one end against baffle 13 or baffle 13 may be placed after liner 5 is inserted.

The ends 16 of inner shell 3 are preferably belled out to aid in the rapid insertion of flanged sleeves 17. It will be noted that insulating material 5 is removed to form a space 18 allowing room for the expansion and contraction of end 16 of liner 3. This space 18 may be formed when material 5 is cast, or may be removed mechanically thereafter.

The specific castable or moldable insulating materials that I have found most suitable in practicing this invention are "Panelag," "Insulag" and "Sil-O-Cell C-3." These are trade names. Quigley Co., 56 West 45th Street, New York city, states "Panelag" is good for temperatures up to 1700° F. while "Insulag" is good up to 2000° F., and that either one when mixed with water forms a plastic cement material which hardens into an insulating block. Johns-Manville Co., 292 Madison Ave., New York city, states "Sil-O-Cell C-3" is a coarse, granular form of calcined diatomaceous silica, which mixed with water forms a plastic cement which hardens into a block good for temperatures up to 2000° F. The exact composition of "Panelag," "Insulag" and "Sil-O-Cell C-3" are secrets, but they are sold by said companies in the open market with directions as to the amount of water to be added, and the other mixing procedure.

"The Refinery Catalog 1942," Gulf Publishing Company, Houston, Texas, lists suitable insulating cements on pages 96, 116, 239, 414, 449, 479, 508, 535 and elsewhere. A mixture of roughly 50% asbestos fibre and 50% Portland cement mixed with just enough water to make it plastic is also suitable, but is not preferred.

In order to provide for the effect of pressure fluctuations in conduit 2, a series of breather holes 19 are preferably spaced in a line around the axis of inner shell 3 where the pressure may be transmitted into the porous, or semiporous, heat insulating material 5, and thus preventing pressure changes on the material with resultant collapse of inner shell 3 and heat insulating material 5.

A stiffener ring 21 may be provided in the form of an inwardly concave ring around liner 3 covering the line of holes 19. The left side of the drawing being considered as the up-stream side and the right hand side as the down-stream side, (see arrow marked flow), it will be noted the stiffener rings 21 are preferably welded to inner shell 3 at a number of alternate spaced points on opposite sides of ring 21, the welds on opposite sides being staggered as shown in the left half of the drawing. Other modes of attachment give comparable results, for example in the right half of the drawing is shown a form where ring 21 is continuously welded around the circumference. Continuous welds of both sides are never employed as then holes 19 would be useless.

In order to keep as much of the high temperature fluid as possible out of the packing material 5 a nipple 22 may be provided having an outwardly belled end sealed to the interior of said inner shell at a point up-stream of the sleeve 17, and sleeve 22 may extend down-stream of the up-stream edge of sleeve 17.

Operation

The operation of the conduit is as follows:

The high temperature fluid so far as it retains its high temperature is confined in inner shell 3 which is formed of suitable alloy steel or other alloy material resistant to the high temperature

and other conditions existing therein, and parts 3, 17, 21, 22 and 18 are preferably made of such material. Due to the lack of structural strength of thin inner shell 3, it is impossible to confine all of the fluid to the interior of shell 3. However sleeve 17 and nipple 22 are designed to deflect the hot fluid so that it will tend to stay inside of shell 3.

However some of the hot fluid necessarily passes through breather holes 19 and some will work its way into the heat insulating material 5. As long as this amount is small it will have lost its heat by the time it has penetrated heat insulating material 5 to contact outer shell 4. However it is desired to prevent this material from channelling between outer shell 4 and insulating material 5, or from channelling in heat insulating material 5. This channelling is prevented or greatly minimized by baffle plate 18. Baffle plate 18 is preferably sealed to the outer shell 4 and extends inwardly to a position overlapping the flanges on sleeve 17. Obviously this construction will bring the fluid back into the central shell 3 so that progressive channelling of large amounts of fluid is rendered unlikely.

If large amounts of hot fluid come in contact with outer shell 4 by channelling this contact will form hot spots, and these hot spots will cause outer shell 4 to lose its stress resistance, which may result in a dangerous break in the conduit or other accident.

It will be noted that the flange of sleeve 17 and the end of the outer shell 4, the flanges 6, plate 18, and the ends of heat insulation 5 all terminate in substantially the same plane transverse to the longitudinal axis of the conduit. This is important, as in a long line it may be desirable to take out one section of the conduit without moving the other sections. With the construction shown this may be done by merely unbolting studs and nuts 7 and 8 at both ends of the desired section, and removing the section by sliding it out of the conduit at right angles to the longitudinal axis without substantial longitudinal movement of the remainder of the conduit. Some former insulated pipes (not shown) are made with telescoping portions, or other construction, in which it would be practically impossible to remove a section of the conduit without an enormous amount of work in moving the two ends of the conduit longitudinally to permit untelescoping.

It is believed obvious that I have provided a high temperature conduit capable of carrying out the objects of the invention as enumerated above.

It is understood that while the drawing and descriptive matter of this specification illustrate a specific example wherein my invention is of particular benefit, other obvious applications can be made. The scope of my invention is therefore subject only to the limitation of the appended claims.

Having described my invention, I claim:

1. A conduit for high temperature fluids comprising in combination a pipe section comprising an outer imperforate stress-bearing shell, an inner perforated heat resisting shell and an intermediate heat insulating shell, attachment means comprising flanges secured to each end of said stress resisting shell, means to draw adjacent pairs of said flanges together, a gasket between adjacent flanges of adjacent sections, an annular imperforate baffle plate sealed to said imperforate shell and extending inwardly toward said inner shell, the ends of said inner shell being belled outwardly, a sleeve in each end of said inner

shell projecting therefrom, the projecting portion of said sleeve ending in an external imperforate flange extending outwardly to a point overlapping the inward extent of said annular plate, a nipple having an outwardly belled end sealed to the interior of said inner shell at a point upstream of the sleeve in the end of said inner shell, said nipple overlapping said sleeve in a downstream direction, the perforations in said inner perforated shell being spaced in a line around the axis of said inner shell, and a ring exterior of said inner shell and spaced to cover all of the perforations in one of said lines, said ring being secured by welding at its upstream side to the inner shell.

10 2. A conduit for high temperature fluids comprising in combination a pipe section comprising an outer imperforate stress-bearing shell, an inner perforated heat resisting shell and an intermediate heat insulating shell, attachment means secured to each end of said stress resisting shell, an annular imperforate baffle plate sealed to said imperforate shell and extending inwardly toward said inner shell, a sleeve in each end of said inner shell projecting therefrom, the projecting portion of said sleeve ending in an external imperforate flange extending outwardly to a point overlapping the inward extent of said annular plate, a nipple sealed to the interior of said inner shell at a point upstream of the sleeve in the end of said inner shell, said nipple overlapping said sleeve in a downstream direction, the perforations in said inner perforated shell being spaced in a line around the axis of said inner shell, and a ring exterior of said inner shell and spaced to cover all of the perforations in one of said lines, said ring being secured at its upstream side to the inner shell.

20 3. A conduit for high temperature fluids comprising in combination a pipe section comprising an outer imperforate stress-bearing shell, an inner perforated heat resisting shell and an intermediate heat insulating shell, a sleeve in each end of said inner shell projecting therefrom, the projecting portion of said sleeve ending in an external imperforate flange a nipple sealed to the interior of said inner shell at a point upstream of the sleeve in the end of said inner shell, said nipple overlapping said sleeve in a downstream direction, the perforations in said inner perforated shell being spaced in a line around the axis of said inner shell, and a ring exterior of said inner shell and spaced to cover all of the perforations in one of said lines, said ring being secured at its upstream side to the inner shell.

30 4. A conduit for high temperature fluids comprising in combination a pipe section comprising an outer imperforate stress-bearing shell, an inner perforated heat resisting shell and an intermediate heat insulating shell, an annular imperforate baffle plate sealed to said imperforate shell and extending inwardly toward said inner shell, a sleeve in the end of the inner shell projecting therefrom, a nipple sealed to the interior of said inner shell at a point upstream of the sleeve in the end of said inner shell, said nipple overlapping said sleeve in a downstream direction, the perforations in said inner perforated shell being spaced in a line around the axis of said inner shell, and a ring exterior of said inner shell and spaced to cover all of the perforations in one of said lines, said ring being secured at its upstream side to the inner shell.

40 5. A conduit for high temperature fluids comprising in combination a pipe section comprising

an outer imperforate stress-bearing shell, an inner perforated heat resisting shell and an intermediate heat insulating shell, an annular imperforate baffle plate sealed to said imperforate shell and extending inwardly toward said inner shell, a sleeve in each end of said inner shell projecting therefrom, the projecting portion of said sleeve ending in an external imperforate flange extending outwardly to a point overlapping the inward extent of said annular plate, the perforations in said inner perforated shell being spaced in a line around the axis of said inner shell, and a ring exterior of said inner shell and spaced to cover all of the perforations in one of said lines, said ring being secured at its upstream side to the inner shell.

6. A conduit for high temperature fluids comprising in combination a pipe section comprising an outer imperforate stress-bearing shell, an inner heat resisting shell and an intermediate heat insulating shell, an annular imperforate baffle plate sealed to said imperforate shell and extending inwardly toward said inner shell, a sleeve in each end of said inner shell projecting therefrom, the projecting portion of said sleeve ending in an external imperforate flange extending outwardly to a point overlapping the inward extent of said annular plate, and a nipple sealed to the interior of said inner shell at a point upstream of the sleeve in the end of said inner shell, said nipple overlapping said sleeve in a downstream direction.

7. A conduit for high temperature fluids comprising in combination a pipe section comprising an outer imperforate stress-bearing shell, an inner perforated heat resisting shell and an intermediate heat insulating shell, a sleeve in the end of the inner shell projecting therefrom, a nipple sealed to the interior of said inner shell at a point upstream of the sleeve in the end of said inner shell, said nipple overlapping said sleeve in a downstream direction, the perforations in said inner perforated shell being spaced in a line around the axis of said inner shell, and a ring exterior of said inner shell and spaced to cover all of the perforations in one of said lines, said ring being secured at its upstream side to the inner shell.

8. A conduit for high temperature fluids comprising in combination a pipe section comprising an outer imperforate stress-bearing shell, an inner heat resisting shell and an intermediate heat insulating shell, an annular imperforate

baffle plate sealed to said imperforate shell and extending inwardly toward said inner shell, and a sleeve in each end of said inner shell projecting therefrom, the projecting portion of said sleeve ending in an external imperforate flange extending outwardly to a point overlapping the inward extent of said annular plate.

9. A conduit for high temperature fluids comprising in combination a pipe section comprising an outer imperforate stress-bearing shell, an inner heat resisting shell and an intermediate heat insulating shell, a relatively short sleeve in the end of said inner shell projecting therefrom and an annular imperforate baffle plate sealed to said imperforate shell and extending inwardly toward but out of contact with said inner shell.

10. A conduit for high temperature fluids comprising in combination a pipe section comprising an outer imperforate stress-bearing shell, an inner perforated heat resisting shell and an intermediate heat insulating shell, an annular imperforate baffle plate sealed to said imperforate shell and extending inwardly toward said inner shell, the perforations in said inner perforated shell being spaced in a line around the axis of said inner shell, and a ring exterior of said inner shell and spaced to cover all of the perforations in one of said lines, said ring being secured to the inner shell.

11. A conduit for high temperature fluids comprising in combination a pipe section comprising an outer imperforate stress-bearing shell, an inner perforated heat resisting shell and an intermediate heat insulating shell, the perforations in said inner perforated shell being spaced in a line around the axis of said inner shell, and a ring exterior of said inner shell and spaced to cover all of the perforations in one of said lines, said ring being secured to the inner shell.
